ATTORNEYS

UNITED STATES PATENT OFFICE

JOHN ROCKE, OF BLOOMINGTON, ILLINOIS

GEARING FOR WASHING MACHINES

Application filed July 15, 1926. Serial No. 122,558.

This invention relates to gearing for washing machines, and more particularly to means for adjusting said gearing to compensate for wear or discrepancies that might 5 arise in manufacture.

One of the objects of the invention is in the provision of driving mechanism for washing machines, wherein there is included gearing of the worm and gear type, there being also provided a special means for adjusting the worm with respect to the worm gear, to compensate for wear, as well as to provide for an efficient meshing of said gear members.

15 Another object is in the provision of a simple and efficient means for adjusting the position of a worm and worm gear, which are included in the power driving mechanism of a washing machine.

20 Other objects will appear in the following specification, taken in connection with the annexed drawings, in which—

Fig. 1 is a side elevation of a washing machine, with portions thereof broken away for 25 a more detailed disclosure;

Fig. 2 is an enlarged detail, in plan, of the special adjustment mechanism between the worm and worm gear; and

Fig. 3 is an end elevation of the parts 30 shown in Fig. 2.

Referring to the drawings, there is shown in Fig. 1 a washing machine of a type wherein an agitator member 10 is disposed in the bottom of a tub 11, said agitator being driven 35 by a vertically disposed shaft 12, projecting through an opening in the bottom of the tub and supported in a column 13. A driven gear 14 is fixedly attached to the lower end of the vertical shaft and is adapted to be reciprocated by the hereinafter described 40 driving mechanism.

It might be stated at this time that as far 45 as the washing machine is concerned, the present driving and gearing mechanism is adapted to be used upon any type of washing machine, wherein the washing element is a member adapted to be reciprocated.

Again, with respect to the special driving 50 and gearing mechanism disclosed herein, there appears the well known electric mo-

tor 15, securely attached to the framing of the washer, and driving a pulley 16 through the belt member 17. A worm 18 has power transmitted thereto directly from the pulley, and said worm meshing with the worm gear 55 19 operates to rotate the stub shaft 20, which carries a crank member 21 of well known design. Pivotaly attached, as at 22, to the crank member, is the rack bar 23, which completes the power connection between driven gear 14 and the crank arm, operating, obviously, to agitate the driven gear, due to its reciprocation.

The present application is directed particularly to the manner of adjusting the worm 65 18 with respect to the worm gear 19, and in Figs. 2 and 3 of the drawings, there have been shown enlarged details of these portions, the same not appearing in detail in Fig. 1.

With respect to the worm and gear connection, it might be stated that this manner of transmitting power is well known, but without some means provided for varying 75 the position of the worm with respect to the worm gear, under some circumstances, we will say wear or defective manufacture, considerable noise attends the movement of these gears.

Applicant, after much experimentation in attempting to overcome this undesirable noise, devised the present means for varying the position of the worm with respect to the worm gear. It is true that varying of the 85 position of worm gears with respect to worms has been heretofore accomplished, but applicant has devised not only a simple means for attaining the result desired, but also one wherein the adjustment may be 90 quickly and readily effected, and by persons other than those skilled in mechanics. This mechanism for adjusting the worm includes the following structure:

The gear casing 24 surrounds the worm and gear. The worm shaft 25 projects through that part of the casing 24 which provides the supports for the bearing members for the worm, such projecting portion being designated 95 26, to which is fixedly attached the pul-

ley 16, the latter being driven as heretofore described.

The worm is supported at one side in a bearing 27 of the oilless type and composed of bakelite impregnated with graphite. A 5 felt washer is shown at 28, there being a steel washer 29 pressed into the end of the bearing support 30. The actual worm, as stated before, is designated as 18 and meshes with the before-mentioned worm gear 19. A ball bearing is shown at 31, disposed in a manner to take up the thrust of the worm. The opposite end of the worm shaft 25 is also supported in an oilless bearing 32 made of the 10 composition bakelite impregnated with graphite, the support for this oilless bearing being shown at 33. The support 33, at this end, is made adjustable in order to vary the position of the worm with respect to the 15 worm gear. This adjustment is effected in the following manner. The bearing support 33, as may be clearly seen in Fig. 2, is movable in a direction towards the worm gear a slight distance, unless restricted. Means for 20 restricting this movement in an adjustable manner is accomplished by supporting the end of the bearing and the worm shaft in the cap 34, capable of slightly varied positioning with respect to the gear casing 24. 25 This varied positioning may be seen perhaps most clearly in Fig. 3. The cap is connected to the casing by three bolts, designated 35, which bolts are threaded into receiving portions in the gear casing. The apertures in 30 the cap 34, however, through which the bolts project, are slightly larger than the bodies of the bolts, therefore permitting a degree of adjustment of the cap member with respect to said bolts. An adjustment screw 36 is 35 threaded into that part of the gear casing surrounding the worm in a manner to force the bearing support 33, and therefore the worm, towards the worm gear 19. A lock nut 37 is provided to fixedly position the 40 adjustment member 36.

With respect to the operation of the adjustment mechanism above described, it is thought clear that said adjustment of the worm with respect to the worm gear is effected by loosening the bolts 35, then turning the screw 36 to move the worm to the desired position with respect to the worm gear, and thereafter tightening the bolts 35 in a manner to securely position the cap with respect to 45 the gear casing and therefore the worm, with respect to the worm gear.

In the actual manufacture of this mechanism, the structure is so designed that the worm normally assumes the correct position 50 with respect to the worm gear without the necessity of adjustment of the screw 36. However, in case of wear on the gears, and the necessity of moving the worm closer into engagement with the worm gear, it is 55 merely necessary, as above stated, to loosen

the bolts, make the adjustment, and thereafter tighten the bolts. The actual adjustment is never so pronounced as to cause any damage to the bearing 25 by moving the shaft slightly out of line.

It may be seen from the above that not only an efficient, but a simple, mechanism has been devised to overcome any noise that might attend the improper meshing of the worm and gear, and this mechanism not only readily accessible, but readily and quickly adjusted.

What I claim is:

In gearing for washing machines or the like, a worm gear and a driving worm therefor, a worm and gear casing, an aperture in said casing, a cap member provided with a bushing for supporting the worm shaft, said bushing projecting freely into said aperture, an adjusting screw engaging the bushing to vary its position within the aperture, and means for fixedly connecting the cap member to the casing in the position set by the adjusting screw, comprising bolt members passing through holes in the cap and into the casing, the bodies of the bolt members having smaller diameters than the holes in the cap.

In testimony whereof I have hereunto affixed my signature.

JOHN ROCKE.
